UNITED STATES PATENT OFFICE.

WILLIAM F. FOWLER AND CHARLES H. MEAD, OF INDIANAPOLIS, INDIANA.

APPLE-BAKER.

987,058.

Specification of Letters Patent.

Patented Mar. 14, 1911.

Application filed November 22, 1909. Serial No. 529,497.

To all whom it may concern:

Be it known that we, WILLIAM F. FOWLER and CHARLES H. MEAD, citizens of the United States, and residents of Indianapolis, in the county of Marion and State of Indiana, have invented certain new and useful Improvements in Apple-Bakers, of which the following is a specification.

This invention relates to electrical apple bakers, and the object of our improvement is to provide a sanitary device for baking or cooking apples, and is designed to be used in the windows of restaurants and other public places where the public may observe the process of such baking or cooking. We attain these objects by means of the electrical cooking device illustrated in the accompanying drawings, in which—

Figure 1 is a sectional elevation of our device taken on the line 1—1 in Fig. 2; Fig. 2 is a view, the upper half of which shows a top view of our baker and the lower half of which shows a sectional view taken along the line 2—2 in Fig. 1; and, Fig. 3 is a diagram showing the electrical circuit of our baker.

Similar numerals of reference indicate similar parts throughout the several views.

Referring to the drawings, the dished disk 1 is composed of any suitable metal, such as polished aluminum, having the flange 2 formed on its peripheral edge and the outer upturned flange 3 formed on the peripheral edge of said flange 2.

The cover 4 is preferably made of transparent glass in order to expose the apples to view while they are being cooked.

A plurality of vertically extending tubes 5, having closed top ends, are formed integral with and on the top side of said dished disk 1, and spaced sufficiently far apart to prevent the apples, which are placed on said tubes to be cooked as described later, from touching each other.

The cylinder 6 is formed on the under side of the dished disk 1 to provide a housing for the insulating disk 7, which is composed of a refractory electrical insulating material, such as porcelain, and the heat insulating disk 14, preferably composed of asbestos. Said disk 7 rests upon the disk 14 and the latter is supported by the ring 15 which in turn is supported by the foot members 16.

The posts 10, which are composed of the same material as that in the disk 7, are formed on the top side of and integral with

said disk 7 and correspond in number to and arranged to extend into and fit the bores of the tubes 5.

The helical coils 9 are formed integrally with or connected in series with the spiral coil 8 and composed of an electrical resistance wire, such as German silver wire, having its ends 11 and 13 connected with the switch 12, and the latter is connected with the service lines in the usual manner to admit an electric current to said coils 8 and 9. Said spiral coil 8 is embedded in the disk 7 in a plane parallel to and near the top surface of said disk, so that the heat generated in said coil will be easily radiated to the dished disk 1, and each of the helical coils 9 is embedded in a post 10 near the peripheral surface of such post, so that the heat generated in said helical coils will be easily radiated to the tubes 5 to cook the apples placed over such tubes.

The tubes 19 are formed of any suitable metal, such as aluminum, with both ends open and with their bores sufficiently large to fit loosely over the tubes 5.

An opening is made through the core portion of each apple to be baked to remove the core, and a tube 19 is inserted in such core opening to prevent the apple from sticking to the tubes 5 while being cooked.

The operation of our device is as follows:—The apples with the tubes 19 in them are placed over the tubes 5, the cover 4 placed in position over the tubes 5 on the dished disk 1 and an electric current turned on the coils until the apples are baked, when such apples are removed from the baker with the tubes 19 still in them and such tubes 19 removed from the apples afterward.

What we claim as new and desire to secure by Letters Patent, is—

1. An electrical apple baker comprising a disk having a plurality of vertical integrally formed posts composed of a refractory electrical insulating material, a spiral coil of electrical resistance wire embedded in said disk, a helical coil of electrical resistance wire embedded in each of said vertical integrally formed posts of said disk and connected in series with said spiral coil, a glass bell adapted to cover the heat producing portion of the baker, and open ended tubes adapted to be inserted in the apples to prevent them from sticking to the baker while being cooked.
2. An electrical apple baker comprising a

pan having a cylindrical housing formed on its under side, a plurality of vertical tubes formed integral with and on the upper side of said pan, a disk having a plurality of vertical integrally formed posts composed of a refractory electrical insulating material in the upper portion of said cylindrical housing and its vertical integrally formed posts fitted in the bores of said vertical tubes of said pan, a spiral coil of electrical resistance wire embedded in said disk, a helical coil of electrical resistance wire embedded in each of said vertical integrally formed posts of said disk and connected in series with said spiral coil to form a continuous electric circuit, a heat insulating disk secured in said

cylindrical housing under said electrical insulating disk, a glass bell adapted to rest on said pan and cover said vertical tubes of said pan, open ended tubes adapted to be fitted over the vertical tubes of said pan and in the openings made in the apples by removing their cores to prevent the apples from sticking to the vertical tubes while being baked.

In testimony whereof we affix our signatures in the presence of two witnesses.

WILLIAM F. FOWLER.
CHARLES H. MEAD.
